(57) **CLAIM**

The ornamental design for a flashlight with receptacle for latch, as shown and described.

DESCRIPTION

FIG. 1 is a top perspective view of a flashlight with receptacle for latch;

FIG. 2 is a bottom perspective view of my invention;

FIG. 3 is right side elevation view of my invention;

FIG. 4 is a left side elevation view of my invention;

FIG. 5 is a top plan view of my invention;

FIG. 6 is a bottom plan view of my invention;

FIG. 7 is a front elevation view of my invention;

FIG. 8 is a rear elevation view of my invention;

FIG. 9 is a top perspective view of a second embodiment of a flashlight with receptacle for latch;

FIG. 10 is a bottom perspective view of a second embodiment of my invention;

FIG. 11 is a right side elevation view of a second embodiment of my invention;

FIG. 12 is a left side elevation view of a second embodiment of my invention;

FIG. 13 is a top plan view of a second embodiment of my invention;

FIG. 14 is a bottom plan view of a second embodiment of my invention;

FIG. 15 is a front elevation view of a second embodiment of my invention; and,

FIG. 16 is a rear elevation view of a second embodiment of my invention.

The broken line showing of a flashlight, portion of a flashlight or mounting structure in the drawings forms no part of the claimed design.

The break lines in the drawings indicate that the appearance of any portion of the flashlight with receptacle for latch between the break lines forms no part of the claimed design.

1 Claim, 4 Drawing Sheets
